UNITED STATES PATENT OFFICE.

MASON CASE, OF LOS ANGELES, CALIFORNIA.

DESIGN FOR A DOLL OR STATUETTE.

Application filed February 9, 1922. Serial No. 611. Term of patent 3½ years.

To all whom it may concern:

Be it known that I, MASON CASE, a citizen of the United States, residing in the city of Los Angeles, county of Los Angeles, and State of California, have invented a new, original, and ornamental Design for a Doll or Statuette, of which the following is a specification, reference being had to the accompanying drawing, forming part thereof.

Figure 1 is a front elevation of a doll or statuette showing my design; and

Figure 2 is a side elevation thereof.

The portions shaded in vertical lines are made in red and the portions shaded with the cross lines are made in black.

I claim:

The ornamental design for doll or statuette, substantially as shown and described.

MASON CASE.
